UNITED STATES PATENT OFFICE.

HENRY G. ELFBORG, OF CHICAGO, ILLINOIS.

NUT-LOCK.

1,306,418.

Specification of Letters Patent. Patented June 10, 1919.

Application filed August 21, 1917. Serial No. 187,399.

To all whom it may concern:

Be it known that I, HENRY G. ELFBORG, a citizen of the United States, residing at Chicago, in the county of Cook and State of Illinois, have invented certain new and useful Improvements in Nut-Locks, of which the following is a specification.

This invention relates to a nut lock, and its purpose is to provide an improved device for preventing the accidental removal of a nut from the bolt with which it is used.

In this highly developed art most locking devices are embodied in or adapted to be used with modified forms of nuts, so that the locking device cannot be manufactured as a separate and independent commodity to be used with standard nuts, but the nuts themselves must be specially constructed at great expense. It is the principal object of the present invention to provide an efficient locking device for use with any of the standard forms of nuts. A further object is to provide a modified form of washer having parts adapted to coact with a standard nut in order to lock it in position on a bolt. Another feature is the provision of a device having parts to engage a standard nut externally, and having an aperture which is eccentrically located with respect to the threaded aperture of the nut, so that a frictional grip and binding action are produced when a locking device and nut are applied to the bolt, thus preventing loosening of the nut due to vibration or abrasion. An important advantage of the present invention is that it exerts an efficient locking action in all positions of the nut on the bolt, so that the nut may be tightened or loosened at any time without decreasing the locking effect of the device.

Other objects and advantages will appear more fully from the following specification, taken in connection with the accompanying drawings, in which several embodiments of the invention are illustrated.

In the drawings—

Figure 1 shows a perspective view of a bolt and nut securing certain members together, my improved locking device being employed therewith.

Fig. 2 shows a side elevation of the nut and locking device shown in Fig. 1.

Fig. 3 shows a side elevation of the nut and locking washer before the corners of

the latter have been turned upward to engage the sides of the nut.

Fig. 4 shows a sectional view of a modified form of the device illustrated in Figs. 1, 2, and 3.

Fig. 5 shows a sectional view through the device illustrated in Fig. 4, taken on the line 4—4.

Fig. 6 shows a sectional view, taken on the line 6—6 of Fig. 4.

Fig. 7 shows another form of my invention used in connection with a nut and bolt for securing two members together.

Fig. 8 shows a side elevation of the locking device illustrated in Fig. 7 with the nut seated thereon.

Fig. 9 shows a view of the locking washer illustrated in Fig. 8 with the nut removed.

Fig. 10 shows a plan view of another form of my invention.

Fig. 11 shows a sectional view, taken on the line 11—11 of Fig. 10; and

Fig. 12 shows a plan view of the locking washer shown in Fig. 10, with the nut and wear plate removed.

Although this improved locking device is adapted to be used with nuts in any position or location where it may be desired to prevent the accidental removal of a nut from a bolt, I have for the purposes of illustration shown the invention in Fig. 1 as employed in connection with a bolt 15 and a standard nut 16 for securing the fish plates 17 to a railway rail 18. The bolt is threaded, as shown at 15^a, in the usual way, being provided at one end with a head 15^b, and being engaged on the threaded portion by the nut 16, which in the embodiment illustrated is a square nut, although the invention is capable of use with hexagonal nuts and various other forms. The nut lock 20 comprises a sheet steel plate, which is preferably square, and has the corners 20^a adapted to project beyond the lateral faces 16^a of the nut. In its initial form the corners of this plate project in the manner illustrated in Fig. 3, but in the final embodiment of the locking washer they are turned upwardly, as shown in Fig. 2, to engage the lateral faces of the nut, so that as the nut is turned on the bolt the washer will turn with it. This plate 20 is provided with a threaded aperture 21, which is eccentrically located with respect to the threaded aperture 16^b of the nut when

the nut and washer are in assembled relation, so that the threaded apertures 21 and 16^b have substantially the relation shown in Figs. 2 and 3. It will be seen, therefore, 5 that when the nut and washer are applied to the bolt the offset relation of the threaded aperture will cause the washer to force the nut into binding engagement with the bolt and firmly hold the nut against accidental 10 movement on the bolt. Although the nut may be moved by means of a wrench or the like, the movement of the nut by the direct engagement of the fingers or the accidental removal of the nut from the bolt are effectually prevented. It will be understood 15 that in the application of this form of my invention, the nut and washer are first placed in assembled relation before being applied to the bolt.

20 Figs. 4, 5, and 6 illustrate a modified form of the device shown in Figs. 1, 2, and 3. In this modified form a substantially square plate 25 is employed, but instead of being turned in an annular relation with respect to 25 the lateral sides of the nut, as in the preceding embodiment of the invention, this plate is provided with flanges 26 on its lateral sides, which are turned upwardly, as shown in Figs. 5 and 6, forming a rectangular recess adapted to receive the nut. The 30 plate is provided with a threaded aperture 27, which is eccentrically located, that is, it is displaced from the central point of the plate, so that in the application of the device to a bolt a locking pressure is produced. In the application of this form of the invention to a bolt, the washer is first 35 placed in assembled relation with respect to a nut, and the two members are then applied to the bolt by means of a wrench.

40 In Figs. 7, 8, and 9, I have illustrated still another form of the invention. For convenience in illustrating this form I have shown a bolt 30 engaged by a standard nut 45 31 for holding together two members 32 and 33. The locking device is embodied in a washer 34, of circular or other suitable form, having a centrally located threaded aperture 35 adapted to engage the threaded 50 part of the bolt 30. In this form of the invention the locking effect is produced by means of a curved shoulder 36, which projects from the face of the washer with its inner surface 36^a located so that its center 55 37 is displaced from the center of the washer and the center of the aperture 35. After placing the nut and washer together and applying them to the bolt, it will be seen that the corners of the nut 31 will ride on the 60 surface 36^a, as illustrated in Fig. 6, so that the washer will be forced in a direction transverse to the axis of the bolt, and thus set up an effective locking action which will prevent accidental removal of the nut, the 65 nut being forced in a direction transversely

of the bolt opposite to the direction in which the washer is forced. This form of the invention requires but a slight modification of the usual washer, and may be constructed with very slight expense.

The form of the invention illustrated in Figs. 10, 11, and 12 has been illustrated in connection with a bolt 40 and standard nut 41. The locking device comprises a cup-shaped washer 42, having a threaded aperture 43 eccentrically located with respect to the periphery of the washer and the inner circular surface 42^a thereof. In order to prevent undue wear upon the annular surface 42^a of this washer, I prefer to employ in connection with this form of the invention a wear plate 44, which is in the form of a sheet metal plate underlying the nut 41, and having transversely extending bow-shaped lugs 44^a which engage the sides of the nut, 85 so that the plate will rotate therewith. The rounded surfaces of the lugs are adapted to ride upon the inner downwardly converging wall 42^a of the washer 42, and because of the eccentric location of the threaded aperture in the washer, the application of the nut to the bolt will result in forcing the nut transversely to the axis of the bolt, thereby setting up a pressure on the bolt which will effectually prevent accidental removal of the nut. In this form of the invention the washer is preferably applied to the bolt before the nut is placed thereon. In each form of the invention the aperture through the locking washer is preferably 90 threaded to reduce the wear on the threads of the bolt.

Although several embodiments of the invention have been illustrated for purposes of explaining the principle of the invention, it 105 will be understood that my improvement may be embodied in still other forms without departing from the spirit of the invention as defined in the appended claims.

I claim:

1. In combination, a bolt, a standard nut threadedly engaging said bolt, and a threaded washer having a part engaging said nut to set up a binding frictional grip transversely of said bolt between said nut and said bolt.

2. In combination, a bolt, a nut threadedly engaging said bolt, and a locking washer seating against the end face and engaging the outer sides of said nut and having an eccentrically located aperture to be closely fitted by said bolt.

3. A locking device comprising a metal plate having parts adapted to engage the lateral sides of a nut and having an eccentrically located aperture adapted to be displaced from the aperture of the nut when the nut and washer are in assembled relation, the aperture in said plate being of the same size as the aperture in said nut.

4. In combination, a bolt, a standard nut 25
threadedly engaging said bolt, a plate seat-
ing against said nut and having parts en-
gaging the nut to prevent relative angular
5 movement of said nut and plate, said plate
having a threaded aperture therethrough
displaced from the threaded aperture of said
nut when said nut and plate are in assem-
bled relation.
- 10 5. In combination, a bolt, a standard nut
threadedly engaging said bolt, and a plate
having a part to engage a lateral surface of
said nut, said plate being further provided
15 with a threaded aperture adapted to engage
said bolt, said aperture and said part of said
plate being disposed to effect a transverse
binding action of said plate and nut on said
bolt.
6. In combination, a bolt, a standard nut
20 threadedly engaging said bolt, and a lock-
ing washer threadedly engaging said bolt
and having parts engaging the lateral sides
of said nut to prevent relative transverse
and angular movements of said washer and
- nut, the aperture in said washer being ec- 25
centrically located with respect to the aper-
ture in said nut.
7. In combination, a bolt, a standard nut
threadedly engaging said bolt, and a locking
washer threadedly engaging said bolt and 30
having non-resilient flanges engaging oppo-
site lateral faces of said nut to prevent rela-
tive angular and transverse movements of
said washer and nut, the aperture of said
35 washer being eccentrically located with re-
spect to the aperture of said nut.
8. In combination, a bolt, a standard nut
threadedly engaging said bolt, and a locking
washer having parts adapted to engage the
lateral sides of said nut and having an ec- 40
centrically located aperture therethrough,
the walls of said aperture in said washer
being arranged to engage opposite sides of
the threaded portion of said bolt when said
45 washer and said nut are assembled thereon.

In testimony whereof, I have subscribed
my name.

HENRY G. ELFBORG.
